UNITED STATES PATENT OFFICE.

CHARLES B. FOSTER, OF BUFFALO, NEW YORK.

OPERATING MECHANISM FOR DRAIN-PLUGS.

1,071,515.

Specification of Letters Patent. Patented Aug. 26, 1913.

Application filed March 30, 1907, Serial No. 365,562. Renewed December 19, 1911. Serial No. 666,841.

To all whom it may concern:

Be it known that I, CHARLES B. FOSTER, a citizen of the United States, residing at Buffalo, in the county of Erie and State of New York, have invented certain new and useful Improvements in Operating Mechanism for Drain-Plugs, of which the following is a specification.

This invention relates to mechanism for opening and closing the drain plug of a wash bowl or similar structure, and has for its object to enable the user, by manipulating a handle, to open or close the drain plug without the necessity for immersing the hand in the water and without the use of chains or similar attaching means which tend to obstruct the wash bowl and interfere with the washing operation.

A further object of the invention is to so construct the apparatus that the plug-operating devices serve to hold or lock the plug in its raised position, preventing accidental dropping or lowering of the same under pressure.

The invention consists in the features of construction and combination of parts hereinafter described and claimed.

In the drawings Figure 1 is a longitudinal sectional view taken through a wash bowl, showing, in elevation, the operating mechanism of the present invention; Fig. 2 a longitudinal sectional view showing the plug lowered; Fig. 3 a similar view showing the plug raised; Fig. 4 a view taken on line 4—4 of Fig. 2.

The mechanism is applied to a wash bowl 5 of any suitable style or shape, in the bottom of which is located a bushing 6 which serves as a drain hole. The mouth 7 of the drain opening is beveled or flared and serves as a seat for a plug 8 which is beveled around its periphery to conform to the flaring of the mouth of the bushing. The bushing, around its mouth, is provided with a flange 9 which is entered into a recess 10, in the bottom of the bowl, to afford a water tight joint, and the bushing has screwed onto its projected lower end a casing 11 which comprises a neck 12 screw threaded 50 to receive the end of the bushing, which neck is provided at its upper end with a flange 13, which abuts against the lower wall or floor

of a depending overflow chamber 14 which is formed integrally with the bowl structure, and merges into an overflow passage 15 formed on the rear or non-exposed surface of the bowl. The bowl, near its upper edge, is provided with overflow holes 16 which communicate with the overflow passage 15, for the purpose of providing an outlet for surplus water and prevent flooding of the bowl. The bushing, immediately below its mouth, is provided, in its wall, with openings 17, which communicate with the overflow chamber, and serve to convey the water therefrom to the interior of the bushing, and thence through the trap to the drainage system. The casing, below the neck 12, on one side, is provided with a protuberant cam chamber 18, and the lower end 19 of the casing, below the cam chamber, is in the form of a slip joint adapted to connect with the trap or drain pipe, not shown, which connects with the drainage system for the house. The cam chamber is of vertically elongated 75 formation, being provided with flat side walls 20, and a curved end wall 21, as shown in Figs. 2 and 3.

The drain plug has, on its under face, a boss 22, into which is entered a rod 23, 80 which rod is screw threaded into a head 24, which comprises part of a cage 25 having radiating arms 26, preferably three in number, which abut against the wall of the cylindrical bushing within which the cage is 85 adapted to rise and fall. The arms connect, at their lower extremities, with a ring 27, of substantially equal diameter with the cylindrical wall of the bushing. The ring rests upon the bowl by a cam finger 28 moving within the cam chamber, which cam finger is formed to have an acting face 29 curved on the arc of a circle. The cam finger is mounted upon the squared end 30 of a rock shaft 31, which extends in transverse relation with respect to the flat side walls of the cam chamber, and the cam is so swung that when it is in its lowermost position, as indicated in Fig. 2, its curved acting face will rest against the lowermost portion 95 of the curved wall 21 of the cam chamber, in which position it can be swung inwardly and upwardly until it occupies the position shown in Fig. 3, in which the center portion 100

of the curved acting surface of the cam will abut against the outer portion of the curved wall 21, which abutment prevents further movement of the cam. When the 5 cam finger is in its uppermost position the extreme end of the finger will project outwardly into the interior of the casing 11, immediately below the ring 27 of the cage, and the tip of the cam finger, thus projected, 10 will occupy a position below the main portion of the cam finger, so that it will be impossible, by a down pressure of the plug, to force the cam out of its raised position. Any pressure thus exerted on the plug will 15 rather have the effect of driving back the cam into tighter contact with the upper wall of the cam chamber, thereby affording a lock which prevents the accidental dropping or forcing down of the plug. The curved 20 acting surface of the cam furthermore enables the cage ring to lie smoothly and evenly upon the cam as the plug is raised and lowered.

The extreme end of the shaft 31 is provided with a bearing stud 32, which is journaled within a small boss 33 on one of the side walls of the cam chamber, and immediately opposite the boss is a journal sleeve 34 which is screw threaded on its end 25 to receive a cap 35, which cap is intended to act as a gland for the compression of a packing ring 36 which surrounds the shaft. In order to prevent retraction of the shaft a collar 37 is provided, which collar, in combination with the journal stud 32, provides a smooth bearing for the rotation of the shaft. The cam shaft 31 is connected with a horizontal transmission shaft 38 by means of a coupling 39, and the transmission shaft 40, in the form shown in Fig. 1, has on its end a bevel pinion 40 which meshes with a bevel pinion 41 on the end of a vertical actuating shaft 42, which shaft has on its end an operating handle 43 located above the 45 bowl and within convenient reach of the user. The vertical actuating shaft and the horizontal transmission shaft are both journaled within a bracket 44, which serves to hold the two pinions in mesh with one another.

In the arrangement of the mechanism shown in the drawing, the operating shaft 42 is passed through a mounting within a faucet 56, the handle 43 being above the 55 faucet, as shown in Fig. 1. This arrangement is a convenient one, in that the faucet handle 57 and the drain handle 43 are both in close proximity to one another, which improves the appearance of the bowl and 60 promotes the convenience of the user. At the same time it will be understood that the invention is not limited to an arrangement of this kind, since the handle can be positioned at any suitable point, and can be 65 used in connection with faucets which do

not permit of the mounting hitherto described.

In use, when it is desired to raise the plug from the closed position shown in Fig. 3, the handle 43 is either turned or lifted, depending upon the bevel connection employed, which movement of the handle imparts rotation through the transmission shaft and the cam shaft to the cam. The rounded acting face of the cam bears against the edge of the cage ring, so that as the cam shaft is turned the cage will be raised, and with it the plug. When the parts are raised, as indicated in Fig. 3, the cam will afford a lock for the plug, which prevents it from being lowered by direct pressure, or in any manner except by the proper operation of the parts. The cage is slidably mounted within the casing, but at the same time sufficiently fills the space to prevent wobbling or displacement of the plug when in raised position, and the interstices or openings in the cage are of sufficient size to permit the easy discharge of water without obstruction. At the same time, when it is desired, for any reason, to 90 clean the discharge passages, the cage, plug and stem can be bodily removed and the cam turned back so as to provide no appreciable obstruction during the cleaning operation. In ordinary circumstances, the actuating 95 mechanism will be entirely hidden by the bowl, the handle only appearing above the surface, so that the appearance of the bowl and the surrounding structure will not be impaired. In the present arrangement, the 100 cam shaft moves through an arc of about 180 degrees when working from closed to open position, and the relative size of the meshing bevel pinions is such that a fraction of a revolution of the handle will be sufficient to 105 open the drain. In order, however, to obviate the necessity for careful adjustment of the intermeshing gears, a complete gear wheel 41 is shown, although but a portion of such gear wheel actually intermeshes with 110 the companion gear wheel, and, so far as actual results are concerned, the segment only of the entire wheel might be used. By employing the completed wheel, however, there is no necessity for careful adjustment, 115 since the parts will coöperate, no matter in what position the pinions are when brought into mesh. The device as a whole is one which is simple in construction and adds to rather than detracts from the appearance of 120 the bowl or other similar structure to which it is applied.

What I claim as new and desire to secure by Letters Patent is:

In mechanism of the class described, the 125 combination of a drain passage provided with a protuberant cam chamber, a rotatable cam shaft passing through the cam chamber from side to side thereof, a cam mounted on the shaft and having a curved 130

acting face, and adapted to be drawn back into the cam chamber to leave the drain passage unobstructed, a plug adapted to close the passage, a slid able mounting for the 5 plug, adapted, when raised, to bear upon the cam at a suitable point to force the cam back into the cam chamber and prevent the

plug from being lowered under pressure, and means for operating the cam, substantially as described.
